(57) **CLAIM**

The ornamental design for a handle grip for valves, as shown and described.

DESCRIPTION

FIG. 1 is a top, front, right perspective view of a first embodiment of a handle grip for valves showing our new design;

FIG. 2 is another top, front, right perspective view with a component in a different position;

FIG. 3 is a front elevational view thereof;

FIG. 4 is a left side elevational view thereof;

FIG. 5 is another left side elevational view with the component in the position of FIG. 2;

FIG. 6 is a top plan view thereof;

FIG. 7 is a top plan view thereof with the component shown in the position of FIG. 2;

FIG. 8 is a top, front, right perspective view of a second embodiment of a handle grip showing our new design;

FIG. 9 is another top, front, right perspective view with a component in a different position;

FIG. 10 is a front elevational view thereof;

FIG. 11 is a left side elevational view thereof;

FIG. 12 is another left side elevational view with the component in the position of FIG. 9;

FIG. 13 is a top plan view thereof; and,

FIG. 14 is a top plan view thereof with the component in the position of FIG. 9.

The broken lines shown in the figures are for the purpose of illustrating environment which form no part of the claimed design.
